Int. Cl. D16—03, 04

U.S. Cl. D61—1

Fig. 4.

Fig. 2.

Fig. 1.

FIG. 1 is a front view in elevation of an overhead projector showing my new design;

FIG. 2 is a left side elevational view thereof;

FIG. 3 is a right side elevational view thereof;

FIG. 4 is a top plan view thereof;

FIG. 5 is a rear elevational view thereof;

FIG. 6 is a bottom plan view thereof; and

FIG. 7 is a cross-sectional plan view taken along lines 7-7 of FIG. 3 thereof.

I claim:

The ornamental design for an overhead projector, as shown.
